COMB RACK

Kenneth A. Allen, 1914 Carlisle Ave, and Harlow W. Roder, 3058 Hamlin Ave., both of Racine, Wis.

Filed May 12, 1961, Ser. No. 65,147

Term of patent 14 years

(Cl. 86—10)

FIG. 1 is a front elevational view of a comb rack, showing our new design.

FIG. 2 is a side elevational view of the comb rack; the side opposite is the same as the side shown.

FIG. 3 is a bottom plan view of the comb rack.

FIG. 4 is a top plan view of the comb rack.

FIG. 5 is a rear elevational view of the comb rack.

We claim:

The ornamental design for a comb rack, substantially as shown and described.
